UNITED STATES PATENT OFFICE

161,962

TOY FIGURE

Peter G. Plante, Fairfield, Conn., assignor to Norco Of Bridgeport, Inc., Bridgeport, Conn., a corporation of Connecticut

Application March 9, 1950, Serial No. 8,427

Term of patent 3½ years

(Cl. D34—4)

To all whom it may concern:

Be it known that I, Peter G. Plante, a citizen of the United States, residing at Fairfield, in the county of Fairfield and State of Connecticut, have invented a new, original, and ornamental Design for Toy Figure, of which the following is a specification, reference being had to the accompanying drawing, forming part thereof.

In the drawings:

Fig. 1 is a front elevation of a toy figure, showing my new design.

Fig. 2 is a side elevation as seen from the left in Fig. 1.

Fig. 3 is a rear elevation.

Fig. 4 is a side elevation as seen from the left in Fig. 3.

The essential features of my design reside in the portions shown in full lines.

I claim:

The ornamental design for a toy figure, substantially as shown and described.

PETER G. PLANTE.
